UNITED STATES PATENT OFFICE.

SAMUEL HERMANN, OF CINCINNATI, OHIO.

TRUNK.

SPECIFICATION forming part of Letters Patent No. 337,328, dated March 2, 1886.

Application filed July 20, 1885. Serial No. 172,168. (No model.)

To all whom it may concern:

Be it known that I, SAMUEL HERMANN, a citizen of the United States, and a resident of Cincinnati, in the county of Hamilton and State 5 of Ohio, have invented certain new and useful Improvements in Trunks, of which the following is a specification.

My invention relates to trunks, and particularly to that kind of trunks in which the 10 outer casing or box incloses a revolving cylinder divided into compartments for the various articles which it is intended to contain. Its object is to provide a ready means of access to any of the various compartments without disarranging the contents of the other compartments.

With this object in view my invention consists of the outer case or box, which is preferably a trunk of ordinary construction, and a 20 cylinder mounted to revolve within the trunk, so as to bring the openings of the different compartments to the top, the cylinder being locked in place in any desired position whether the trunk is open or closed.

In the accompanying drawings, forming part 25 of this specification, in which like parts are indicated by similar reference-letters throughout the various views, Figure 1 is a perspective view of an open trunk provided with my improvements. Fig. 2 is a transverse vertical section through the closed trunk and in front of one of the cylinder ends. Fig. 3 is a transverse vertical section taken centrally through the revolving cylinder. Fig. 4 is an enlarged elevation of a portion of one end of the trunk looking from the inside. Fig. 5 is an elevation of another portion of the end, illustrating my spring-fastening which locks the cylinder to prevent it from revolving. Fig. 6 is a central vertical transverse section of a modified 35 form of my revolving cylinder.

The body of the trunk A is in general construction and form like those in common use. To each end on the inside is secured a metal 40 plate, B, as shown in Fig. 4. This plate has a vertical slot rounded at the lower end, and diverging outward upon each side toward the top to receive trunnions b, upon which the cylinder C revolves. The end of the trunk is 45 slotted from the top down to the trunnion-bearing, as shown at b', to permit the trunnions of the cylinder to pass down to their bearings.

The trunnions b project from circular plates which are secured to the ends of the central compartment, D. This central compartment 55 is an open frame, to which are hinged upon diagonally opposite sides the segments E and F, the bottoms e and f, when closed, forming the bottom and top of the tray D. The segment E is preferably divided into three compartments, and the opposite segment F left undivided. This I find to be the most convenient arrangement for trunks intended for ordinary use; but for sample-trunks these compartments may be subdivided both longitudinally and transversely to suit the convenience of the different tradesmen. The compartments E and F are provided with hinged covers e' and f', as shown in dotted line, Fig. 3, and these covers, as well as the segments, 60 are retained in the closed position, as clearly shown at g, Fig. 1.

The spring-fastening H is a strap of steel, which has an oblong opening punched in it, and upon opposite sides of this opening the metal 75 is stamped up to form inclines h. The straps are secured to the inside of the trunk ends with the inclines h, and the openings between them in the path of the pins h', which project from the ends of the tray D. The upper end of the strap projects above the body of the trunk, to furnish a hold by which it is thrown back to release it from the pins h', and the cylinder can be revolved to bring either segment to the 80 top or bottom of the trunk.

It will be seen that the tray D, which is intended for the larger articles of clothing, is accessible from either side, so that it will not be necessary to remove all the articles to get 85 at those in the bottom.

In the modification shown in Fig. 6 there is no central tray, the cylinder being divided longitudinally by a partition, and the whole cylinder divided into five compartments. In both of the sectional views, Figs. 3 and 6, the 90 hinged covers of the compartments are represented by heavy sectional lining, while the stationary parts are shown by the light sectional lining.

What I claim as new, and desire to secure 95 by Letters Patent, is—

1. The combination, as specified, of the trunk-body A, and inner revolving cylinder, the said cylinder being pivoted to revolve within

the outer case or body and divided into compartments closed by hinged covers, which form part of the outer shell of the said cylinder, with the latch H h , and pins h' , to lock the said cylinder in the desired position.

2. The combination, substantially as herein-before set forth, of the trunk-body or outer casing A , with the inner revolving cylinder, said cylinder having a central compartment consisting of the open frame D , and two segments, E and F , the bottoms e and f of said segments forming, alternately, the bottom and top of said compartment D , as the segment E or F is brought on top by revolving the cylinder upon its trunnions, the said segments E

and F being hinged to the frame D at its diagonally-opposite edges.

3. In a trunk of the character described, the combination, as specified, of the body A , provided upon the inner ends with the bearings B , and latches H , of the inner revolving cylinder having the trunnions b and pins h , said cylinder being divided into compartments D , E , and F hinged together as shown, and for the purpose specified. 20

SAMUEL HERMANN.
